UNITED STATES PATENT OFFICE.

MADISON L. JOHNSON, OF GALENA, ILLINOIS.

MEANS FOR PREVENTING LOCOMOTIVE DRIVING-WHEELS FROM SPINNING.

SPECIFICATION forming part of Letters Patent No. 296,576, dated April 8, 1884.

Application filed August 17, 1883. (No model.)

To all whom it may concern:

Be it known that I, MADISON L. JOHNSON, of Galena, in the county of Jo Daviess and State of Illinois, have invented a new and useful Improvement in Means for Preventing Locomotive Driving - Wheels from Spinning, which improvement is fully set forth in the following specification, reference being had to the accompanying drawings, in which—

10 Figure 1 is a representation of a portion of a locomotive, showing my invention applied; and Fig. 2 is a transverse sectional view of the same.

The object of my invention is to prevent 15 the driving-wheels of locomotives from spinning or slipping on the rail. This I accomplish by placing in the smoke-box of a locomotive, as shown in the drawings, two pans of funnel shape, A A, opposite each other and 20 facing the blast-pipes H H. The smaller ends of the pans extend through the sides of the smoke - box, where each has a valve, C C, and where the pipes G G are connected on either side, which run back to a point midway 25 between the driving-wheels and the rails. I also place at the top of the smoke-box, at the point where the smoke - stack I is affixed, a damper, D, with a crank - arm, E, attached, and a controlling-rod, F, which leads back to 30 the cab of the locomotive. The pans A A are covered at their face with a grating of wire-cloth, to prevent the larger cinders from entering. The valves C C, if so desired, can be

attached to the rod F, and operated in connection with the damper D. By pushing the 35 rod F forward, it closes the damper and partly cuts off the draft that should go through the stack I, and all the smoke, dust, and small cinders that cannot escape through the small opening K are equally divided and are forced 40 through the pans A A and the pipes G G, and are deposited on the rail directly under the driving-wheels, the heat of the smoke and dust drying the rail, if it be moist; and the cinders being ground or crushed between the 45 wheel and the rail increases the friction, thereby enabling the wheel to keep the rail and preventing it from slipping or spinning.

What I claim as my invention or discovery, and desire to secure by Letters Patent, is—

The combination, with the wire-gauze-covered pans, arranged within the smoke-box of a locomotive, having their lateral tubes provided with valves, the pipes G G, leading therefrom to the track-rails, the damper D, 55 provided with a central annular opening, its bearing - shaft having crank arm connecting with the controlling-rod F, and the blast-pipes H H, arranged within the smoke - box, all adapted to operate substantially as shown and 60 described.

MADISON L. JOHNSON.
